UNITED STATES PATENT OFFICE.

EUGÉNE WORMS AND ALEXANDER SIGISMOND ZWIERZCHOWSKI, OF PARIS, FRANCE.

VELOCIPEDÉ.

SPECIFICATION forming part of Letters Patent No. 451,588, dated May 5, 1891.

Application filed November 24, 1890. Serial No. 372,397. (No model.) Patented in France October 2, 1890, No. 208,612, and in England October 31, 1890, No. 17,454.

To all whom it may concern:

Be it known that we, EUGÉNE WORMS and ALEXANDER SIGISMOND ZWIERZCHOWSKI, both citizens of the French Republic and residents of Paris, France, have invented certain Improvements in Bicycles and other Velocipedes, (for which patents have been granted in France, No. 208,612, dated October 2, 1890, and in Great Britain, No. 17,454, dated October 31, 1890,) of which the following is a specification.

Our invention relates in part to a novel construction of the ball-bearings, in part to a novel arrangement and construction of the saddle-support, and in part to an improved construction and arrangement of the brake.

The invention will be fully described hereinafter, and its novel features carefully defined in the claims.

20 In the accompanying drawings, which serve to illustrate our invention, we have shown it applied to a bicycle.

Figure 1 is a side elevation, and Fig. 2 a front elevation, of the bicycle on a comparatively small scale. Fig. 3 is a vertical section on a much larger scale, taken through the wheel-hub and gearing in the plane of the wheel-axis. Figs. 4, 5, and 6 are fragmentary sectional views, also on a large scale. These

30 will be hereinafter described.

R represents the main wheel of an ordinary bicycle. D is the curved "backbone" or frame, and R^x is the smaller trailing-wheel. N is the tubular upright sleeve secured to the curved frame O, in which sleeve is mounted the stem I of the fork J. On the stem I is fixed the handle-bar R', provided with handles S. These are substantially like the ordinary features of a bicycle.

40 We will first describe the gearing whereby the wheel R is driven at a speed different from that of the pedal-shaft.

Referring especially to Figs. 3 and 4 for illustration, A is the pedal-shaft, and P' are the pedals thereon. These latter may be of the usual kind. The hub or nave R² of the larger wheel R is mounted on the pedal-shaft, but it is not fixed thereto, as in the most common constructions. On the axle A is secured

50 a toothed wheel B, the teeth of which gear

with those of a pinion C, rotatively mounted on a stud E, set in the inner face of the branch of the fork J on that side of the wheel R. Fixed to or integral with the pinion C is a toothed wheel D, the teeth of which gear with those of a pinion F fixed on the hub of the wheel R. As the pinions C and F have a less number of teeth than the respective gear-wheels B and D, it follows that when the pedal-shaft A is rotated by the rider it will 55 impart to the wheel R through said gearing an axial velocity greater than that imparted to said shaft by the rider.

All of the rotating parts (see Fig. 3) have ball-bearings, and while such ball-bearings 65 are, *per se*, well known, our construction presents some novel features. On the lower ends of the respective branches of the fork J are mounted rings K K', the attachment being by means of a screw-threaded stem i on the 70 ring, which is passed up through the end of the branch and secured firmly thereto by a nut. These rings are screw-threaded internally, and into them are screwed, respectively, the outer ball-boxes H H'. These boxes 75 may be screwed in or out for adjustment, and when adjusted they may be fixed each by a set-screw b.

Fig. 4 is an inner face view of the ring K', with the box H', and balls a therein. The 80 box may have longitudinal grooves m in its screw-threaded periphery to receive the point of the set-screw, as seen in Fig. 4.

Secured firmly on the shaft A are collars G and G', which serve as abutments, respectively, for the balls in the boxes H and H'. The hub of the wheel B is made to serve as the collar G'. The hub of the wheel R is slipped onto the pedal axle from the right, as seen in Fig. 3, and when it is in place the 90 balls a at the left are embraced between a collar I' on the pedal axle or shaft A and a ball-box H² of annular form, screwed into that end of the wheel-hub. At the other or right-hand end of the wheel-hub the balls a 95 are embraced between the collar G' and a ball-box H³, screwed into that end of the hub. At the left-hand end of the hub the box H² is exterior to the balls, while at the other end the balls are exterior to the box H³. The in-

tegral wheels C and D are also mounted in ball-bearings on the stud E in a manner similar to that described. With this system of ball-boxes a ring is dispensed with and the balls are completely housed, which insures very easy rolling with very little wear and friction.

- We will now describe the construction and arrangement of the saddle-mounting, with especial reference to Fig. 1, where the saddle is represented in two positions. Ordinarily the saddle of a bicycle is mounted on the arched frame O; but in our bicycle it is mounted on the sleeve N through the medium of a bracket N' thereon and a set-screw. M is the saddle-bracket, which is in the nature of a bar bent until its two branches stand about at right angles, as shown. The vertical branch of this bracket fits in a socket in the bracket N', and when adjusted therein it may be fixed by the set-screw, and the horizontal branch of said bracket M passes through a sleeve or eye q on a base-plate Q, in which sleeve it is secured by a set-screw. The plate Q supports the saddle proper Q' on coil-springs, which are housed in telescoping sockets c, the lower sections of which are mounted on the plate Q, and the upper sections to the saddle-frame. One of the telescoping sockets is represented in section in Fig. 1. An advantage due to this construction is this: If a spring should give way the saddle would still be supported by the sockets. By turning the horizontal branch of the bracket M in the sleeve q, the vertical branch may be passed upward through the bracket N', as seen in dotted lines in Fig. 1. This construction permits considerable latitude in the vertical adjustment of the saddle.
- Figs. 5 and 6 are detail views illustrating the construction of the brake device, the former being a sectional view of the lower part of the sleeve N and adjacent parts, and the latter a longitudinal section of one of the handles S on the handle-bar. f is the brake-shoe, pivotally mounted at d, and coupled to an operating-wire e, which passes up through the tubular stem I, and out through one of the tubular arms of the handle-bar R', to a nut g (see Fig. 6) in the handle S. This nut traverses a long pitched screw h fixed at one end to the handle S, which latter is adapted to be turned by the hand on the handle-bar. The rider is

thus enabled to set the brake by merely rotating the handle S axially with his hand. The handle may be fixed on the handle-bar by a set-screw v, if required. This set-screw is driven through the ferrule k of the handle, as seen in Fig. 6.

Having thus described our invention, we claim—

1. The combination, with the axle provided with a removable collar G' and a shoulder I', of the wheel-hub R², ball-boxes II² and II³, screwed into the respective ends of the said hub, and the balls a embraced between the respective boxes and the shoulders on the axle, substantially as set forth.

2. The combination, with the fork J and the shaft A, of the internally-screw-threaded rings K and K', secured to the respective branches of the fork, the ball-boxes II and II', screwed into the respective rings, the collars G and G' on the shaft A, and the balls in the respective ball-boxes, substantially as set forth.

3. The combination, with the upright sleeve N of a velocipede, of the bracket N', secured thereto and provided with a socket to receive the saddle-bracket M and with a set-screw, the said saddle-bracket having two branches which stand substantially at right angles with each other, and the saddle mounted on the horizontal branch of said bracket M, substantially as set forth.

4. The combination, with the saddle and its supporting-springs, of the telescopic casings c, which house said springs, substantially as set forth.

5. The combination, with the tubular stem I, the tubular handle-bar R', and the handles S, mounted rotatively on said bar and bearing a screw h in its interior, of the brake-shoe f and its spring, the nut g on the screw h, and the wire e, connecting the brake-shoe with said nut, substantially as set forth.

In witness whereof we have hereunto signed our names in the presence of subscribing witnesses.
